UNITED STATES PATENT OFFICE

HERMAN LIEBER, OF JACKSON HEIGHTS, NEW YORK

DESIGN FOR A SHOE

Application filed August 17, 1932. Serial No. 44,624. Term of patent 3½ years.

To all whom it may concern:

Be it known that I, HERMAN LIEBER, a citizen of the United States, residing at Jackson Heights, in the county of Queens and State of New York, have invented a new, original, and ornamental Design for Shoes, of which the following is a specification, reference being had to the accompanying drawing, forming part thereof.

The figure is a perspective view of a shoe, showing my new design.

I claim:

The ornamental design for a shoe, as shown.

HERMAN LIEBER.
